Alex Pascoo, New York, N. Y.

Application November 16, 1943, Serial No. 510,455

3 Claims. (Cl. 116—119)

This invention relates to improvements in bookmarks.

The main feature of the invention resides in a bookmark which may be clamped upon the rear cover of a book and automatically mark the pages of the book as they are read and turned from front to rear.

Another feature of the invention is to provide a bookmark in which the marker is adjustable relative to its support to facilitate the movement of the same toward the rear cover of the book as the number of the pages to be read gradually decreases.

Another feature of the invention is the provision of a bookmark primarily intended for use by book readers which may be applied to and removed from the cover of a book without mutilation thereof, and which is capable of long life from one book to another.

A further feature of the invention is to provide a bookmark which is capable of being made of precious metals as an expensive personal article, or which may be made of inexpensive materials containing indicia and distributed for advertising good-will purpose.

Other features of the invention will become apparent as the following specification is read in conjunction with the accompanying drawing, in which:

Figure 1 is a fragmentary perspective view of a book showing my bookmark in use thereon.

Figure 2 is an enlarged detail vertical sectional view on the line 2—2 of Figure 1.

Figure 3 is a vertical transverse sectional view on the line 3—3 of Figure 2.

Figure 4 is a perspective view of the bookmark per se.

Figure 5 is a collective perspective view of the bookmark with the parts in separated relation and illustrating a modified form of clamp.

Figure 6 is a front elevation of the marker with an advertising sign thereon.

Referring to the drawing by reference characters, and at present to the form of the invention illustrated in Figures 1 to 4 inclusive, the numeral 10 designates a bookmark in its entirety which is constructed in accordance with my invention. The book mark 10 includes a clamp 11 which is formed from a length of resilient material, such as steel, brass, or the same may be made of plastic or Celluloid. The clamp 11 includes confronting jaws 12 and 13 which are connected together by a loop 14. The free ends of the jaws 12 and 13 are outwardly flared to facilitate their easy insertion upon the cover of a book,

the free end of the jaw 12 extending beyond the plane of the free end of its companion jaw 13. Integrally connected with the jaw 13 and extending at substantially right angles to the clamp 11, is a flat arm 15. Slidably mounted upon the arm 15 is an extension member 16, the same being of flat tubular shape in cross section to receive the arm 15. The top wall of the extension member 16 is provided with an elongated slot 17, the same being closed at its inner end and open at the outer end of the extension member. A stop lug 18 is bent up from the free end of the arm 15 and extends into the slot for engagement with the closed end thereof for limiting the outward sliding movement of the extension member 16 relative to the arm 15.

Slidably carried by the extension member 16 is a carrier 19 in the form of a clip which embraces the extension member 16 but which is clear of the slot 17. Depending from the outer end of the carrier 19 is a flange 20, the same terminating in an eye 21 for hinged receiving a marker 22. The marker 22 is in the form of a wire bail with the terminal ends disposed in the eye 21. The outer end of the extension member 16 is provided with a downwardly extending stop lug 23 for limiting the outward sliding movement of the carrier 19 relative to the extension member 16.

In practice, assume that the bookmark 10 is to be applied to a book in the manner shown in Figures 1 and 2 of the drawing. The clamp 11 is inserted over the rear cover approximately centrally of its width with the arm 15, extension member 16 and carrier 19 extending inwardly from the clamp and clear of the top pages of the book. If the book is relatively thick, the extension member 16 is pulled out relative to the arm 15 so that the carrier 19 will lie on a plane substantially the same as the page to be marked as best illustrated in Figure 2. Further outward adjustment may be obtained by sliding the carrier 19 relative to the extension member 16. After the bookmark has been clamped to the rear cover as just explained, the marker 22 will lie between two pages of the book and as a page is turned, the marker 22 will swing outwardly as illustrated in Figure 2 by the dotted lines and after the page clears the marker, the marker will drop by gravity to mark the next adjacent page. As the thickness of the remaining pages decreases, the carrier 19 may be slid toward the clamp as also may be the extension member 16. Thus it will be seen that a person reading a novel or other form of book from cover to cover may

mark the page automatically as each page is turned.

In Figure 5 of the drawing, a slightly modified form of the invention is illustrated, but in which like parts are designated by the corresponding previous reference characters. The clamp in this form is designated 11a and is formed from a single length of bent wire to form clamping jaws 12a and 13a. The wire is also bent to form an arm 15a which extends at right angle to the clamp and which corresponds to the previously described arm 15. Slidable on the arm 15a is the extension member 16 and slidable on the extension member 16 is the carrier 19 to which the marker 22 is hingedly connected.

In Figure 6 of the drawing, the marker 22 has a sign plate 24 fixed thereto and on which advertising matter may appear. Thus it will be appreciated that the book mark may be made up and distributed for good-will advertising purposes, the advertisement appearing in view during the reading of a book.

While I have shown and described what I consider to be the most practical embodiment of my invention, I wish it to be understood that such changes in construction and design as come within the scope of the appended claims may be resorted to if desired without departing from the spirit of the invention.

Having thus described the invention, what I claim as new and desire to secure by Letters Patent of the United States, is:

1. A bookmark comprising a clamp, a rigid arm connected to and extending substantially at right angle to said clamp, an extension member slidably mounted on said arm, a carrier slidably mounted on said extension member, and a marker hingedly connected to said carrier.
2. A bookmark as set forth in claim 1, including stop means for limiting the sliding movement of the extension member in a direction outwardly away from the clamp, and stop means for limiting the sliding movement of the carrier in a direction outwardly relative to said extension member.
3. A bookmark comprising a clamp, a rigid arm integral with said clamp and extending at an angle relative thereto, an elongated extension member slidably mounted on said arm and having a slot lengthwise thereof which is closed at its inner end, a stop lug adjacent the free end of said arm extending into said slot for engagement with the closed end thereof for limiting the outward sliding movement of the extension member relative to said arm, a carrier slidably mounted on said extension member, stop means on the extension member for limiting the outward sliding movement of the carrier relative to the extension member, and a marker hingedly connected to said carrier.
